(57) CLAIM

The ornamental design for a gaming machine with bonus wheel as shown and described.

DESCRIPTION

FIG. 1 is a front perspective view of a first embodiment of a gaming machine with bonus wheel in accordance with my new design;

FIG. 2 is a front view of the gaming machine with bonus wheel shown in FIG. 1;

FIG. 3 is a back view of the gaming machine with bonus wheel shown in FIG. 1;

FIG. 4 is a left side view of the gaming machine with bonus wheel shown in FIG. 1;

FIG. 5 is a right side view of the gaming machine with bonus wheel shown in FIG. 1;

FIG. 6 is a top view of the gaming machine with bonus wheel shown in FIG. 1;

FIG. 7 is a front perspective view of a second embodiment of a gaming machine with bonus wheel in accordance with my new design;

FIG. 8 is a front view of the gaming machine with bonus wheel shown in FIG. 7;

FIG. 9 is a back view of the gaming machine with bonus wheel shown in FIG. 7;

FIG. 10 is a right side view of the gaming machine with bonus wheel shown in FIG. 7;

FIG. 11 is a left side view of the gaming machine with bonus wheel shown in FIG. 7; and,

FIG. 12 is a top view of the gaming machine with bonus wheel in FIG. 7.

The broken line showing portions of the gaming machine with bonus wheel depicts environment and forms no part of the claim.
